UNITED STATES PATENT OFFICE.

WILBUR H. PECK, OF CHICAGO, ILLINOIS, ASSIGNOR, BY MESNE ASSIGNMENTS, TO TITLE OWNERS COMPANY, A CORPORATION OF MAINE.

CENTRIFUGAL ORE-SEPARATOR.

No. 802,779.

Specification of Letters Patent.

Patented Oct. 24, 1905.

Application filed November 7, 1904. Serial No. 231,742.

To all whom it may concern:

Be it known that I, WILBUR H. PECK, a citizen of the United States, residing at 1003 Monroe street, Chicago, Illinois, have invented certain new and useful Improvements in Centrifugal Ore-Separators, of which the following is a specification.

My invention relates more particularly to centrifugal separators for separation of ores and similar materials of different degrees of specific gravity while in a pulverized or finely-divided state and mixed with water, and belongs to that class having an outer rotatable portion or vessel with a separating surface or area on its inner wall and a differentially-rotatable expansible and contractible inner portion or core which serves as a deflector and which is illustrated and described in the applications for United States Letters Patent for centrifugal separators filed by me June 13, 1904, Serial Nos. 212,429, 212,430, and 212,431, respectively, and also application, Serial No. 231,743, filed by me November 7, 1904, reference to which is hereby made; and my invention consists in the features and details of construction and combinations and associations of parts hereinafter set forth and claimed.

In the drawings, Figure 1 is principally a vertical central section of my improved separator, showing, however, part of the deflector and some other portions of the separator in elevation. Fig. 2 is a detail plan showing the worm-shaft-adjusting mechanism and its drive. Fig. 3 is a cross-section of Fig. 1 on line 3 3 looking in the direction of the arrows. Fig. 4 is an enlarged detail cross-section of one of the deflector bars and covering, showing position of one of the dovetailed channels and fastening devices. Fig. 5 is a longitudinal section of a part of the deflector-covering on line of a row of the fastening devices, showing the latter in elevation. Fig. 6 is a cross-section on line 6 6, Fig. 5, showing position of two longitudinal rows of fastening devices. Fig. 7 is a detail perspective of a fastening device. Fig. 8 is an enlarged detail of a part of the lower end of the deflector in Fig. 1, better showing the means for anchoring and securing the end of the cover. Fig. 9 is a detail of a modified form of fastening device. Fig. 10 is a cross-section of a part of Fig. 9 on line 10. Fig. 11 is a detail of a portion of one of the bars of the

deflector, shown partly in side elevation and, 55 partly in longitudinal central section through its dovetailed channel and showing two fastening devices in position therein, one of which, however, is located in the portion of the channel where the bar is sectioned and 60 shows said fastening device in side elevation.

In making my improved centrifugal separator I provide a rotatable portion or vessel *a*, which I will term a "treatment" vessel. I prefer to locate the treatment vessel in a 65 vertical position and to have it annular in shape with comparatively thin walls, as a tube or pipe, with a small amount of taper, however, from one end to the other and to have it provided with a smooth inner wall or surface, which serves as a separating surface or area *a'*. The treatment vessel is provided with heads or ends *b* and *c*, having extended hollow central hubs or trunnions *d* and *e*, respectively, as shown especially in Fig. 1. I also 70 provide a shaft *f*, extending through the trunnions *d* and *e*, around which the trunnions are rotatably journaled, thus forming bearings for lateral support of the rotatable treatment vessel. This shaft is in turn supported laterally 75 by suitable journal-boxes *g* and *h*, the top one of which is attached to a casting *i* above the upper trunnion supported by columns *j*, which are securely mounted on a base-housing *k* of the separator. The lower journal-box *h* engages the shaft below the lower trunnion and is secured to the base-housing 80 through arms *l*. The shaft is mounted in its journal-boxes *g* and *h* in a slidably manner and is extended through such boxes sufficiently, as shown in Fig. 1, to permit of a 85 desired longitudinal travel. It is supported at its lower end in a suitable step-box *m* in a way to be substantially maintained therein against relative longitudinal movement to 90 the box, so that by the movement of the step-box the shaft will be forced with it either up or down, as the box may be moved. This box *m* is pivotally attached by links *n* to the forked end of the lever *o*, which lever is fulcrumed at *p* to the base-housing of the separator. The opposite end of the lever is secured by links *q* to an internally-threaded nut *r*, which engages a substantial depending rod *s* with its lower end threaded and which is securely and rotatably mounted and well maintained in substantial journal-boxes *t* 100 To the rod, between its journal-boxes, is rig-

idly mounted a worm-wheel *u* for rotating the rod. The worm-wheel contacts at its hubs with the inner ends of the journal-boxes, thus maintaining the rod against longitudinal travel. Meshing with teeth on the periphery of the worm-wheel is a worm *v*, carried and rotated by an adequate substantially journaled shaft *w*, which is rotated in either one direction or the other by the clutch-pulleys *x* and *y*, the two being driven in opposite directions by belts *z* and 2, Fig. 2, traveling in such manner, respectively, so that by movement of the lever *3'* the clutch 3 may be brought into engagement with either one or the other of said pulleys, the threaded rod revolved in either direction desired, thus forcing the nut *r* up or down and rocking the lever *o* correspondingly and effecting a desired longitudinal movement or travel of the shaft *f*.

The base-housing of the separator is provided with two spirally-inclined troughs or compartments 4 and 5, as shown in Fig. 1, terminating in a discharge-spout 6.

The treatment vessel *a* is preferably supported vertically by a thrust-bearing 7 at its lower end, mounted on the upper end of the journal-box *h*, and is secured against upward movement by contact of its upper trunnion 30 against the journal-box *g*. The lower end of the vessel is preferably somewhat enlarged diametrically for a short distance of its length, as shown in Fig. 1, and is provided with a row of nipples 8 around the circumference of the enlargement, which nipples have small openings 8' for the discharge of material and water from the treatment vessel. Within the recess or chamber formed by this enlargement I prefer to provide a suitably-shaped ring 9, containing a series of depressions or pockets, as shown, with large openings at their inner side and converging to small openings registering with the discharge-nipples 8, as shown in Fig. 1. The object of this recessed or chambered ring is to prevent undue lodgment of material at this point.

Within the treatment vessel *a* and to operate in conjunction with it and its separating-surface and differentially rotatable to the treatment vessel and assisting to form a separating channel or passage therein I provide an expansible and contractible composite core, which I will term a "deflector" and which is preferably largely made of or embodies sections 10 of any suitable shape; but I prefer to have them in the form of substantially inflexible T-shaped bars or ribs. I will therefore in the specification and claims mostly speak of these sections as bars, but do not mean to confine myself strictly to that form of section. I prefer to have them extend lengthwise to the separating-surface or axis of rotation and at their outer or circumferential sides to have them lie comparatively close to each other with their stem

portions extending toward the axis of rotation, so that their outer or head portions together or collectively form a circumferential surface or area at least approximately round and quite closely conforming to the contour or shape of the separating-surface. These bars or sections preferably have their outer circumferential surfaces turned or formed convex, so as to present collectively a more nearly round circumferential contour, and with their covering, hereinafter described, to form with the separating-surface a separating or concentrating channel. In the outer circumferential wall of the bars are formed channels or ways 12, as illustrated in Figs. 1, 4, and 11. These channels may be formed in any suitable way or shape desired to subserve the purposes required of them; but I prefer to have them dovetailed in form, located in the median line of the outer or convex T-faces of the bars, and extend the entire length of the bars or sections, and open at the ends of said bars and be adapted to receive and retain from relative radial movement fastening devices, hereinafter described, and hold such devices in place until the same are removed. If the several bars have outer T-faces of sufficient width to make it desirable, more than one channel may be employed in each, located on opposite sides of said median line.

Mounted rigidly on the shaft *f* within the treatment vessel at desired places, as illustrated particularly in Figs. 1 and 3, are hubs, wheels, or outwardly-extended portions 13, provided with radiating-slots 14, Fig. 3, of proper size and suitably located, as illustrated, to receive with slight clearance the stem portions of the T-shaped bars, and preferably at each side of these slots, located longitudinally to them and opening into them, are undercut ways or channels 15, formed by any suitable means desired, having bearing-surfaces extending longitudinally and obliquely to the axis of rotation, as shown in Figs. 1 and 3. Secured longitudinally and obliquely on the sides of the stem portions of the bars 10 at the points where they enter the slots 14 are strips 16, which also have suitable bearing-surfaces and are of size and shape and properly located to register with and properly enter in a sliding manner the oblique undercut ways or channels 15, so that by their engagement therein the bars are held from radial movement, except through the relative movement longitudinally of the shaft carrying the hubs or wheels 13. The bars are thereby concertedly movable toward and from the axis through the longitudinal movement or travel of the shaft. These bars 10 preferably extend nearly the entire length of the treatment vessel, as shown, leaving, however, room at the lower end for a plate or disk 17, with which the ends of the bars contact

in a radially-movable manner. The plate is somewhat removed from the head of the vessel, as shown in Fig. 1, and between the two is interposed a bearing 18, which is preferably 5 of the roller or ball type and serves as means for assisting to support the plate and its superimposed parts and to prevent relative longitudinal travel of the bars forming the deflector and the treatment vessel. At the 10 upper end of the vessel the bars are short enough to permit of the introduction of a disk or plate 19, which contacts with the bars at their upper end also in a movable manner. Thus the two plates form heads or 15 ends or end portions for the collective bars or sections of the deflector.

The upper plate 19 is provided with an upwardly-extended hollow flange or collar 20 near its central part which surrounds the 20 shaft *f* and preferably extends up into an annular chamber in the lower part of the trunnion *d*. Within this chamber and between the end of the flange on the plate and a shoulder on the trunnion is located a thrust- 25 bearing 21, preferably also of the roller or ball type which at this end serves to prevent relative longitudinal travel between the bars of the deflector and the treatment vessel. The plates 17 and 19 are mounted on the 30 shaft *f* sufficiently loose to slide on it, but engage the splines 17' and 19', respectively, so as to be revolved with the shaft. It therefore follows that through the instrumentality of the said plates and the bearings 18 and 21 35 relative longitudinal travel between the plates and sections and the treatment vessel is prevented, while at the same time these former parts and the treatment vessel are differentially rotatable to each other, and the shaft 40 *f*, with its rigidly-mounted parts, are longitudinally movable to the vessel and bars. The travel of the shaft longitudinally may be effected by the mechanism that has been hereinabove described, driven by the belts 2 and 45 2.

It will be seen that by traveling the shaft *f* with its rigidly-mounted parts 13 longitudinally the obliquely-located pieces 16 will be traveled in the ways 15 and be forced toward or from the axis of rotation, thereby 50 moving the bars positively and concertedly either in or out, depending on the direction of longitudinal travel of the shaft, so that the deflector is expanded or contracted diametrically and circumferentially, and through 55 its nearer approach or its recession from the separating-surface the channel or space between the deflector and the separating-surface which constitutes the separating-channel 60 11 will be either decreased or increased in size. The degree of angle or obliqueness of the parts 16 and their associate ways 15 and the distance of longitudinal travel of the shaft are suitably proportioned to secure the 65 amount of expansion and contraction of the

deflector desired, and the bars are preferably so sized that when in a receded or contracted position their adjacent edges at their collective circumferences will be comparatively close together. It then follows that in 70 an extended or expanded position these edges will be somewhat farther apart.

I prefer to provide the plate 17 with a port or opening through it of any suitable size and shape desired for access into the deflector 75 or for other purposes and to cover it with a removable plate or covering 17', Fig. 1.

I prefer to prevent water and material from entering the inside of the deflector formed by the several bars, partly for the 80 reason that it would to some extent interfere with the proper working of the parts of the deflector, and further for the reason that material flowed inside of the deflector from leakage or otherwise would be removed out 85 of the separating-channel, which would prevent its proper separation. As means for accomplishing this purpose I provide a flexible covering 22 over the circumferential area of the collective bars. This covering is pref- 90 erably made of alternate layers of rubber and canvas quite similar to some kinds of rubber belting. It is preferably made in the form of a tube of slightly greater diameter than that of the deflector when the latter is fully 95 expanded, so that the covering can be slid lengthwise over the end of and into place on the circumferential surface of the deflector. The covering is preferably made somewhat longer than the length of the bars and ex- 100 tends somewhat over the plates or head portions at the ends of the bars. Its extreme ends may be made of soft rubber without fiber, if desired, and this with a short distance of the portion of the ends containing 105 fiber are drawn down over the circumferential edges of the end portions or plates 17 and 19, and rings 23 are placed over said ends, as shown in Fig. 1, and in detail in Fig. 8, and the said rings, by means of the tap-bolts 24, 110

are securely clamped down, which compresses or draws the end of the covering into water-tight contact with the end portions or plate, so that fastening the end of the covering is substantially and tightly effected. 115 When it is desired to remove the covering from the deflector, the rings 23 may be removed by removal of the tap-bolts, and the covering may be withdrawn endwise from over the bars.

As means for holding the flexible covering to place around the bars against the action of centrifugal force when little or no water is in the treatment vessel and against torsional friction of the water while water is present in 125 the vessel I provide fastening or retaining devices 25, Figs. 5, 6, 7, 8, and 11, adapted to enter and be maintained in channels in the outer circumference of the bars. I prefer to make these devices with their ends or 130

portions that enter the flexible covering of a retaining form and well secured in the covering, and to make their other ends or portions projecting from the covering, which latter 5 portions are preferably dovetailed in shape. These devices are located in the covering in longitudinal rows, as shown especially in enlarged detail, Figs. 5 and 9, with the rows so spaced as to register with and enter the channels in the several bars from their ends when the covering is slid endwise over the bars and to be withdrawn from the channel when the covering is removed or drawn off endwise from the bars. The channels which are shown 10 longitudinally of the bars in Figs. 1 and 11 and in cross-section in some other figures and are indicated by the numeral 12 are preferably made dovetailed in shape to correspond with the projecting portion of the fastening device. 15

20 A modified form of fastening device is shown in Figs. 9 and 10, where a dovetail-shaped bar 26 is illustrated and serves to unite the several bases of the stem or shank portion of the fasteners which enter and are 25 secured in the covering.

As means for feeding or supplying material to the treatment vessel for separation a pipe 27, Fig. 1, is used, connecting with a hollow fixed casting 28, having an annular 30 opening 29 at its lower side, registering with an annular opening in the feed-chamber 30 on the upper head of the treatment vessel. From this feed-chamber are holes 31 through the upper head of the treatment vessel, communicating with the space within the vessel 35 between its upper head and the upper plate of the deflector. The pipe 27 may be provided with a suitable valve (not shown) to govern the flow of material and water to the 40 vessel, and there is a branch pipe 32 for supplying clean water when desired. This may be provided with a suitable valve (not shown) for governing the flow of clean water.

In operation the treatment vessel is 45 revolved at the desired speed by means of a belt, which may be passed around the raised surface 33 on the vessel, and the deflector is also revolved, but at a desired different rate of speed, by means of application to its pulley 50 34. Initially the deflector is expanded to its fullest extent, thereby reducing or contracting the separating-channel to its proper size for commencement of concentration or separation. The materials to be separated 55 while in a finely-pulverized state and mixed with the desired amount of water to make it flow freely are then fed into the treatment vessel, preferably from a suitable elevated agitator-tank, (not shown,) to which the feed- 60 pipe connects, and passes into the vessel and separating-channel through the agencies that have been described, the heavier portions or concentrates lodging on the separating-surface, while the lighter or waste parts are 65 forced or driven along by and with the water

through the separating-channel to discharge. The washing or scouring action of the water in the channel is principally governed by the amount of differential revolution between the treatment vessel and the deflector, which during concentration or separation is adjusted properly to wash off and move the lighter parts along to discharge, while at the same time permitting the heavier to lodge and accumulate on the separating-surface. As the operation proceeds and the accumulation or accretion is forming in the separating-channel the latter would very soon become too much contracted or filled if there were no compensating agency, and to meet this condition during the concentrating period the inner shaft is traveled longitudinally, as has been explained, and thereby the deflector is gradually and uniformly contracted, thus enlarging the separating-channel by increasing its depth, which in turn is being progressively filled with concentrates. When the deflector has been fully contracted, the feed of material for separation is discontinued, the speed of the treatment vessel considerably decreased, and a flow of clean water introduced by its pipe and flowed through the separating-channel, and at the same time the deflector, through the reverse longitudinal travel of the shaft, is expanded to its initial 9 or maximum size, during which time the accumulated concentrates in the separating-channel are washed out or removed and discharged. If this is not completely accomplished by the time the deflector is fully expanded, flow of clean water is continued for a sufficient additional short time thereafter to fully remove the concentrates, when the flow of clean water may be discontinued, the treatment vessel increased to its proper speed 1 of rotation, and separation may then be resumed. All material and water passed through the separator are flowed out through the spout 6, although the several products which it is desired to keep separate are flowed at different times and diverted by shifting-launders or other desired means to suitable places of deposit.

I desire to state that by the term "water-tight" or "substantially water-tight" in referring to the covering or deflector I mean that part only which is and comes within the zone of the water and in contact with it in the vessel while in operation.

I do not in this application claim certain generic and other features herein disclosed but also disclosed and claimed in my application now pending, Serial No. 212,429, or that are claimed in my applications, Serial Nos. 212,430 and 212,431, which have been allowed, all filed June 13, 1904, or my pending application, Serial No. 231,743, filed November 7, 1904.

What I regard as new, and desire to secure by Letters Patent, is—

1. In a centrifugal ore-separator, the combination of a rotatable treatment vessel having a separating-surface therein, an expandible and contractible deflector within the vessel having sections provided with channels adapted to receive retaining devices and a removable flexible covering around said deflector, having retaining devices with one of their parts embedded in the covering and another of their parts removably engaging said channels. 70
2. In a centrifugal ore-separator, the combination of a rotatable treatment vessel having a separating-surface therein, an expandible and contractible deflector within the vessel having sections provided with channels adapted to receive retaining devices and a removable flexible covering around said deflector, having retaining devices with one of their parts embedded in the covering and terminating beneath its outside surface, and the other of their end portions removably engaging the said channels. 75
3. In a centrifugal ore-separator, the combination of a rotatable treatment vessel having a separating-surface therein, an expandible and contractible composite deflector within the vessel provided with channels in its circumferential wall and a flexible removable covering over the circumference of said deflector having devices extending therefrom and engaging said channels to hold the covering to place. 80
4. In a centrifugal ore-separator, the combination of a rotatable treatment vessel having a separating-surface therein, an expandible and contractible deflector within said vessel having movable bars provided with channels in their outer circumferential walls and a flexible covering over the collective circumference of said bars, having devices protruding from said covering and removably engaging said channels to hold the covering to place. 85
5. In a centrifugal ore-separator, the combination of a rotatable treatment vessel having a separating-surface therein, an expandible and contractible deflector within the vessel provided with channels in its circumferential wall and a substantially water-tight flexible covering over the circumference of said deflector, having devices engaging said channels to hold the covering to place. 90
6. In a centrifugal ore-separator, the combination of a rotatable treatment vessel having a separating-surface therein, an expandible and contractible deflector within said vessel having movable bars provided with channels in their outer circumferential walls and a removable flexible covering over the collective circumference of said bars, having devices engaging said channels for holding the covering to place. 95
7. In a centrifugal ore-separator, the combination of a rotatable treatment vessel, having a separating-surface therein, an expandible and contractible deflector within the vessel having movable bars provided with dovetailed channels in their outer circumferential walls and a flexible covering over the collective circumference of said bars having devices removably engaging said channels for holding the covering to place. 100
8. In a centrifugal ore-separator, the combination of a rotatable treatment vessel, having a separating-surface therein, an expandible and contractible deflector within the vessel having movable bars with undercut ways or channels in their outer circumferential walls and a flexible covering over the collective circumference of said bars having devices projecting therefrom of shape and in position to enter and removably engage the said channels whereby the covering is held to place. 105
9. In a centrifugal ore-separator, the combination of a rotatable treatment vessel, having a separating-surface therein, an expandible and contractible deflector within the vessel, having movable bars provided with dovetailed channels in their outer circumferential walls and a flexible covering over the collective circumference of said bars, having devices projecting therefrom of shape and in position to removably enter and engage the dovetailed channels whereby the covering is removably held to place. 110
10. In a centrifugal ore-separator, the combination of a rotatable treatment vessel having a separating-surface, an expandible and contractible deflector within the vessel having movable bars provided with dovetailed channels on their composite outer diametrical walls and a flexible covering over the collective circumference of said bars, having devices projecting therefrom in longitudinal rows, the respective rows adapted to register with and enter in a retaining manner, the said channels in the several bars, whereby the covering may be slid endwise over the circumference of the deflector and its projecting devices into engagement with the said channels. 115
11. In a centrifugal ore-separator, the combination of a rotatable treatment vessel having a separating-surface therein, an expandible and contractible deflector within the vessel having sections provided with channels adapted to receive retaining devices and a removable flexible covering around said deflector, having retaining devices with one of their parts embedded in the covering and another of their parts removably engaging said channels, an end portion for said sections collectively and the covering removably secured thereto. 120
12. In a centrifugal ore-separator, the combination of a rotatable treatment vessel having a separating-surface therein, an expandible and contractible deflector within the vessel having movable sections, a substantially water-tight flexible covering over 125

the collective circumference of said sections, an end portion collectively for the several sections and a ring secured to said end portion overlapping the end part of the flexible covering and compressing it substantially water-tight to the end portion of the several sections.

13. In a centrifugal ore - separator, the combination of a rotatable treatment vessel 10 having a separating-surface therein, an expandible and contractible deflector within the vessel having movable sections provided with channels on their outer diametrical walls, a substantially water-tight flexible 15 covering over the collective circumference of said sections, having devices engaging said channels in a retaining manner for holding the covering to place, a portion forming an end collectively for said section and a ring 20 secured to the said end portion of the several bars, overlapping the end part of the flexible covering and compressing it substantially water-tight to said end portion.

14. In a centrifugal ore - separator, the 25 combination of a rotatable treatment vessel having a separating-surface therein, an expandible and contractible deflector within the vessel, having movable bars provided with channels in their outer diametrical walls 30 and a substantially water-tight flexible covering over the collective circumference of said bars, devices projecting from said covering located in longitudinal rows, the respective rows adapted to register with and 35 enter the channels from the end of the sev-

eral bars, whereby the covering may be slid endwise over the circumference of said bars and the fastening devices held in said channels, a portion forming an end for the collective bars, and a removable ring secured to 40 said end portion overlapping the end part of the flexible covering and compressing it substantially water-tight to said end portion of the collective bars.

15. In a centrifugal ore - separator, the 45 combination of a rotatable treatment vessel having a separating-surface therein, an expandible and contractible deflector within the vessel, having movable bars provided with dovetailed channels in their outer circumferential walls and a flexible covering over the collective circumference of said bars having secured to it dovetailed pieces engaging said dovetailed channels for holding the covering to place.

16. In a centrifugal ore - separator, the combination of a rotatable treatment vessel having a separating-surface therein, an expandible and contractible deflector within the vessel having movable sections and a 60 substantially water-tight removable covering over the circumference of said deflector having projecting retaining devices, secured to said covering and removably engaging said deflector.
